CLAIM

The ornamental design for a package for a computer cable, as shown and described.

DESCRIPTION

FIG. 1 is a perspective view showing my new package design.

FIG. 2 is a top plan view of the design shown in FIG. 1.

FIG. 3 is a front elevational view of the design shown in FIG. 1.

FIG. 4 is a rear elevational view of the design shown in FIG. 1.

FIG. 5 is a right side elevational view of the design shown in FIG. 1.

FIG. 6 is a left side elevational view of the design shown in FIG. 1.

FIG. 7 is a sectional view, taken in the direction of the arrows, along the section line 7—7 of FIG. 2.

FIG. 8 is a sectional view, taken in the direction of the arrows, along the section line 8—8 of FIG. 2.

FIG. 9 is a sectional view, taken in the direction of the arrows, along the section line 9—9 of FIG. 2; and,

FIG. 10 is a sectional view, taken in the direction of the arrows, along the section line 10—10 of FIG. 2.

The broken lines are for illustrative purpose only and form no part of the claimed design.
